UNITED STATES PATENT OFFICE.

SAMUEL FRANCIS AARON AND SAMUEL HARBERT HAMILTON, OF PHILADELPHIA, PENNSYLVANIA; SAID AARON ASSIGNOR TO THE SCIENTIFIC PRESERVATION COMPANY, OF PHILADELPHIA, PENNSYLVANIA, A CORPORATION OF WEST VIRGINIA.

GAS-GENERATOR FOR FUMIGATION.

No. 854,617.

Specification of Letters Patent.

Patented May 21, 1907.

Application filed July 3, 1906. Serial No. 324,563.

To all whom it may concern:

Be it known that we, SAMUEL FRANCIS AARON and SAMUEL HARBERT HAMILTON, citizens of the United States, residing at 5 Philadelphia, in the county of Philadelphia and State of Pennsylvania, have invented certain new and useful Improvements in Gas-Generators for Fumigation; and we do hereby declare the following to be a full, clear, 10 and exact description of the invention, such as will enable others skilled in the art to which it appertains to make and use the same.

Our invention is directed to improvements 15 in fumigating chests, closets and storage chambers, within which a gas generator is employed for generating gas by the admixture of chemicals for fumigating the contents of the closure.

The invention consists in the construction, 20 combination and arrangement of parts set forth in and falling within the scope of the appended claims.

In the accompanying drawings wherein we 25 have illustrated one embodiment of our invention—Figure 1 is a vertical longitudinal section of a closure which may represent a chest, closet or storage chamber and a separate gas generator-device therein wherein a

30 gas is produced by the admixture of chemicals in a novel way for fumigating the contents of the closure. Fig. 2 is an enlarged vertical section of the gas generator device, the chemical containers being in the condition prior to the admixture of the chemicals 35 for producing the fumigating gas. Fig. 3 is a like view of the gas generator device showing the chemicals in the condition of their admixture by the breaking of separate connected chemical containers and the delivery 40 of the mixed chemicals into a third chemical container in effecting the generation of the gas.

Our invention is designed more particu- 45 larly for the generation of a poisonous gas for destroying moths, carpet beetles, and similar pests and disease germs, and for fumigating woolens, furs, carpets, etc.

The articles to be treated may be con- 50 tained in a chest or closure 1, which may be permanent or portable but air tight and pro-

vided with a lid or door 2, for access to the closure for placing and removing the contents. Within this chest closure is fixed or otherwise placed a gas generator device 55 which includes a box 3, within which is placed the gas generating device. This device consists of three vessels two of which are sealed and connected and suspended one by the other within the box and contain gas producing chemicals and the third vessel seated 60 on the bottom of the box and containing a chemical for the purpose of solidifying the gas producing chemicals after they are delivered therein from the suspended vessels or 65 containers, and the evolution of the gas has taken place. The upper vessel or container 4, is of frangible material preferably of glass suspended by its neck 5, centrally within the box by a cross-bar 6, fixed to the walls of the 70 box about mediately of its height so that the mouth of the neck is open for access preferably above the bar. This frangible vessel contains a fluid which is a part of the gas producing chemicals and its neck is closed by a 75 stopper 7, fitted so as to render the vessel or container air tight and to be readily driven down into the vessel through its neck in the operation of delivering the contents therefrom.

The lower of the connected containers is preferably a bag 8, which may be of paper, cloth or other suitable fabric which may be readily torn open at the bottom; or it may be of other breakable substance. It also 85 contains a chemical 9, either fluid or solid and it is preferably fastened to the neck of the upper suspended container by a string, paste, glue, held by a rubber band or any other means of attachment so that the bag en- 90velops the walls of the glass vessel with an air tight fitting. The jar 10, is of acid proof material within the open top of which the connected chemical containers are centrally suspended. This jar contains a non-gas- 95 producing chemical 11, so that, when the chemicals in the two suspended containers are united or mixed to form a poisonous gas, the admixture of these gas producing chemicals with the chemical in the jar results in a 100 solid or semi-solid which will not spill if upset and so results from an absorption of the

liquid by the chemicals in the jar. The generation of the gas takes place instantly upon the union of the chemicals in the suspended containers. The gas passes from the open 5 jar into the box and into the chest or fumigating chamber, and for this purpose the walls of the box are provided with openings 12, through which the gas passes out as it is generated. The chemical in the jar is provided primarily to semi-solidify the liquid resulting from the mixture of the contents of the suspended retainers by absorbing these liquids and thus prevent the chemicals from being spilled out into the box when the 10 fumigator is made portable but when the structure has a permanent location the jar may or may not contain a chemical, or it may contain a gas producing chemical.

For manipulating the gas generating device that effects the fumigation, means are provided for breaking through the bottom of each of the suspended chemical containers to cause the admixture of the chemicals contained therein and their delivery into the jar 15 in a mixed condition. For this purpose the generator box is preferably mounted immediately under the lid of the chest and a tube 13, depends from the top of the box in alinement with an opening therein and with 20 the neck opening of the suspended chemical container and terminates just above the mouth of the container. In alinement with this tube the lid has an opening 14, closed by a plug 15, and when it is desired to start the 25 fumigating process this plug is removed for access to the interior of the receptacle and a pointed rod 16, is inserted through the opening and through the depending tube into the neck of the suspended container, the mouth 30 of which is preferably flaring, driving the stopper therein down into the container and breaking through its bottom and causing the admixture of the chemical therein with the chemical in the lower suspended container 35 and thereby generating a gas. The rod being further inserted and breaking the lower suspended container causes the combined chemicals now a liquid, to fall into the jar. The gas passes upward and out of the box 40 and into the chest by diffusion and results in fumigation of the interior of the chest, closet, etc. and the destruction of life therein. The box having the separate connected containers renders it convenient to charge them separately with the chemicals, to seal each to prevent their deterioration, and to move the generator to the desired place in the chest or closure without danger of separating the containers or mixing the chemicals; while the 45 provision for mixing the chemicals gives the advantage of hand work through a plug closed opening in the chest. The box is also advantageous in allowing the placing of the charged containers and the removal and re- 50 placing of the broken ones and for this pur-

pose one side of the box may be hinged, and it may be removed from the chest at any time for purposes of recharging, etc.

In inserting the rod it may be thrust with several blows to break out the bottom of the 70 frangible container and to break, tear or split the bottom of the bag to allow the liquid chemical to pass freely out and the rod caused to drop and rest on the bottom of the jar and to stand within the depending tube 75 to clear the opening in the lid so that said opening may be closed by the plug as in Fig. 3 thus rendering the closure air tight and preventing the escape of the poisonous atmosphere, the gas generator continuing to produce gas until the chemicals are exhausted. 80

An important advantage in the use of a poisonous gas for fumigation is its efficacy in destroying insects and disease germs.

The upper suspended vessel is supplied 85 with the chemical through its open neck which is then closed by the stopper and the vessel is set in its suspending seat, the neck for this purpose being formed preferably with a flaring mouth or shoulder. The lower vessel 90 is supplied with the chemical and tightly fitted upon the walls or neck of the suspended vessel so that the bag hangs below the latter and both vessels are sealed. The two vessels may in this way be prepared and mounted 95 as a unitary device.

The suspending of a pair of closed chemical-containing vessels, the upper one by its neck and the lower one from the body of the upper one is to allow the bottom of each to 100 be broken to discharge and mix their contents by a hand operated rod caused to enter the mouth of the upper vessel to break it first and empty its contents into the lower vessel and then to break the bottom of the lower 105 vessel so that the contents of both shall be mixed before they are delivered into a third open receptacle.

While we do not wish to be confined to any particular character of gas or to any particular chemicals because they may be varied according to conditions, yet as to the character of the gas it may be carbonic acid, hydrocyanic acid, hydrochloric acid or a mixture of these gases; or the gases may be bromine, 110 chlorin or some related poisonous gas which it would be dangerous to inhale. To give an example of the chemical liquid and the chemical employed and supposing that it is required to fumigate for disease and stench, the 115 upper vessel would be filled with some dilute acid liquor, say hydrochloric, and the lower vessel would be filled with some chemical that would evolve,—say chlorin (as chlorinated lime) when the acid liquid came in contact with the gas producing chemical. In this operation the liquid chemical from the upper vessel when united with the chemical liquid or solid in the lower vessel forms a 120 chemical combination and gives off (gener- 125 130

ates) a poisonous gas which is death to animal, insect, or germ life. This combination is effected by breaking through the upper vessel and delivering its contents into the 5 lower connected vessel resulting in the production of gas. Then the further breaking through the lower vessel precipitates the resulting chemical mixture upon the third chemical in the jar where the generation of 10 the gas is continued, the fluidity of the mixture being absorbed and chemically combines with the chemical in the jar and solidifies the liquids from which the gas is given off. This non-gas-producing chemical may 15 be some salt of lead which would unite chemically with the resultant liquid calcium chlorid and produce lead chlorid which is a solid and would not spill, but obviously such chemical compounds may be varied.

20 The provision of an air tight chest containing a sealed gas generator and means whereby interior access is had externally of the chest to break the sealed generators within the chest, and allow the means of such access to 25 be sealed within the chest to preserve its air tight character, is a distinguishing feature of our invention and it saves much trouble and prevents danger in the use of the device. The rod may be removed after the suspended 30 vessels are broken or it may be left within the broken vessels to allow the chest openings to be closed.

We claim:

1. In a fumigator, an air tight receptacle, 35 having a normally closed opening, a pair of frangible vessels fixed within said receptacle one below the other, the upper one of said pair having an orifice in alinement with that of the inclosing receptacle and each adapted 40 to contain liquid chemicals for generating gas, and a hand operated rod adapted for insertion through the opening in said inclosing receptacle and in the orifice of the upper vessel of the pair for breaking each of said vessels in succession the upper one first for causing 45 the mixing of its contents with that of the other for producing gas within said air tight receptacle.
2. In a fumigator, an air tight receptacle, 50 a box located therein, and having wall openings, a mixing jar within said box, a necked vessel suspended within said jar for containing a gas producing chemical, a removable stopper closing said neck, a closed vessel depending 55 from said suspended vessel for containing a gas producing chemical, and a rod adapted to be thrust within and through both vessels in succession to break and open them for causing the chemicals to be delivered in a 60 mixed condition therefrom into the jar, whereby a fumigating gas is produced and caused to pass from the box into the closure.
3. In a fumigator, an air tight receptacle, 65 a device located therein for generating a fumigating gas and comprising a box having

wall openings, a mixing jar within said box, a pair of connected vessels one depending from the other, both adapted to contain a liquid chemical, and both closed, and a rod adapted to be driven within and through both vessels 70 to open them to cause the chemicals to be delivered in a mixed condition therefrom into the jar.

4. In a fumigator, a fumigating device comprising a box having openings in its 75 walls, a frangible necked vessel for containing a liquid chemical, means for suspending said vessel by its neck within the box, a fabric vessel connected to and depending from the exterior walls of the frangible vessel, each vessel adapted to contain a chemical, the neck of the upper vessel closed by a stopper, and the lower vessel closed by its connection with the upper vessel, an open 80 mixing jar within which the connected vessels are suspended, and means adapted to be inserted into and forced through the walls of the connected vessels for breaking them to cause their contained chemicals to be mixed and delivered into the mixing jar. 85

5. In a fumigator, a fumigating device comprising a box having openings in its walls, vessels for containing a liquid chemical suspended one above the other, the lower one depending from the walls of the 95 upper one and both rendered air tight, an open mixing jar within which the chemical containing vessels are suspended, and means whereby the connected vessels are caused to be broken open in succession to cause the 100 mixing of the chemical in one with the chemical of the other and the delivery of the mixed chemicals into the mixing jar.

6. In a fumigator, a fumigating device comprising a box having openings, vessels 105 for containing gas producing chemicals suspended one above the other within said box, an open mixing jar into which the contents from said vessels are caused to be delivered, an air tight chest containing said fumigating 110 device and having an opening in vertical alinement with the suspended vessels, a removable plug for said chest opening, and a removable stopper for the upper of the suspended vessels, and means for causing the 115 stopper of said vessel to be driven therein in the operation of breaking the said vessels in succession.

7. In a fumigator, an air tight chest having an opening in its top normally closed by a 120 plug, a box located within said chest and having wall openings, an open mixing jar within said box, a frangible closed vessel suspended within said jar for containing a gas-producing chemical, a fabric vessel depending 125 from said suspended vessel for containing a gas-producing chemical, and a rod adapted to be thrust through the top opening in the chest and through both vessels to break and open them in succession for causing the chemicals 130

to be delivered in a mixed condition therefrom into the jar for the purpose stated.

8. In a fumigator, an air tight receptacle having a top opening normally closed by a plug, a box fixed within said receptacle having an opening in alinement with that of the receptacle, a pair of frangible vessels within the box one below the other the upper one of said pair having an orifice in alinement with that of the box and each adapted to contain chemicals for generating gas, and a hand operated rod adapted for insertion through the openings in said inclosing receptacle, the opening in the box and the orifice of the upper vessel of the pair for breaking each of said vessels in succession the upper one first for causing the mixing of their contents for producing gas within said receptacle.

9. In a fumigator, an air tight receptacle, a group of three vessels therein each for containing a chemical, one below the other the upper pair sealed with the chemicals therein, the lower vessel open at its top and within which the pair of closed vessels depend, and a rod hand operated from outside of the chest for piercing the closed pair to break the bottom of each the upper one first for causing the chemicals to be mixed together for generating gas.

10. A receptacle or chest having an open-

ing, a plug closing said opening, a frangible vessel having an open neck and adapted to contain a gas producing chemical, a stopper closing said neck, a sealed vessel depending from the frangible vessel, and a vessel within which the connected chemical containers are supported, the plug, the stopper and the connected vessels being in alinement, and a rod of suitable dimensions adapted to be passed through the chest opening for breaking through the sealed vessels in succession and allow the opening in the chest to be sealed.

11. In a fumigator, an air tight receptacle having an opening, a pair of frangible vessels each adapted to contain a gas producing chemical, each closed and connected together one above the other, means for supporting said vessels in vertical alinement with the opening in the receptacle, and means applied through said opening for breaking said vessels and means for closing said opening for the purpose stated.

In testimony whereof we have signed our names to this specification in the presence of two subscribing witnesses.

SAMUEL FRANCIS AARON.
